(57) **CLAIM**

The ornamental design for a flex anchoring device for an indwelling urinary catheter, as shown and described.

DESCRIPTION

FIG. 1 is a front elevation view of a flex anchoring device for an indwelling urinary catheter;

FIG. 2 is a right elevation view thereof, the left elevation view being a mirror image thereof;

FIG. 3 is a top elevation view thereof, the bottom elevation view being a mirror image thereof;

FIG. 4 is a back elevation view thereof;

FIG. 5 is a front perspective elevation view thereof;

FIG. 6 is an exploded plan view thereof;

FIG. 7 is an environmental front view thereof, in a condition of use, the backing layer is removed for illustration;

FIG. 8 is an environmental perspective view thereof, in a condition of use, the backing layer is removed for illustration; and,

FIG. 9 is an environmental perspective view thereof, in a condition of use, the backing layer is removed for illustration.

The broken lines in FIGS. 7, 8, and 9 depict environmental subject matter which forms no part of the claimed design.

1 Claim, 9 Drawing Sheets
